The ornamental design for a tire, as shown and described.

DESCRIPTION

FIG. 1 is a perspective view of a tire showing my new design; FIG. 2 is a front view thereof, for which the rear view is the same;

FIG. 3 is a top plan view thereof, for which the bottom plan view is the same;

FIG. 4 is a right side view thereof, for which the left side view is the same;

FIG. 5 is an enlarged view taken along lines 5-5 and 5'-5' in FIG. 2;

FIG. 6 is an enlarged end view taken along line 6-6 in FIG. 4 and line 6'-6' in FIG. 5; and,

FIG. 7 is an enlarged end view taken along line 6-6 in FIG. 4 and line 7-7 in FIG. 5.

In the drawings, the broken lines defining portions of the sidewall and inner bead depict environmental subject matter that forms no part of the claimed design.
